PAPER BURSTER TOY

Otto A. Langos, Chicago, Ill., assignor to Alfred F. Langos, Otto E. Langos, Harold L. Langos, and Matilda R. Langos, partners, doing business as Langson Manufacturing Company, Chicago, Ill.

Application December 17, 1937, Serial No. 180,421

8 Claims. (Cl. 46—195)

My invention relates in general to paper burster toys and more in particular to a cane with mechanism for bursting paper with an explosive noise. The present invention is more particularly an improvement over the structure of one of my earlier patents—No. 1,004,043, issued September 26, 1911.

An object of the present invention is to provide an improved simplified paper burster embodied in a cane having an elongated handle, and paper feeding and bursting mechanism operated by exerting downward pressure on the handle while holding such mechanism against a rigid surface such as the floor, sidewalk, or the like.

A further object of my invention is the provision of a device of this character having relatively few elements, substantially all of which are stamped out and of such configuration that may be quickly and easily manufactured and assembled into a sturdy, efficient, and attractive toy.

A still further object is the provision of a simplified and inexpensive cane type paper burster which will operate with a certainty and with a relatively small amount of pressure so that substantially any child, small or large, may satisfactorily operate the same.

One of the features of my invention is the provision of a simplified and sturdy mechanism with relatively few moving parts so that the device will operate satisfactorily and enjoy a long life under the most abusive treatment.

Other objects and features of my invention will be apparent from the following description taken with the drawings, in which:

Fig. 1 is a side elevation in reduced size of the cane device of my invention.

Fig. 2 is an elevational view with one side of the housing removed, and with the paper supporting, feeding and bursting mechanism in cross-section showing the piston and cylinder in the normal non-operating position.

Fig. 3 is a side elevation of the operating mechanism of the device with one side of the housing removed, and the cylinder broken away to show the position of the piston, at an intermediate position in its paper-bursting stroke, and before the cylinder itself is moved in the housing. The relative downward movement of the housing as between the positions of Fig. 2 and Fig. 3 is readily apparent.

Fig. 4 is a fragmentary elevational view partly in section showing the final paper bursting position of the operating mechanism.

Fig. 5 is an elevational view of the operating

mechanism in the operating position of the structure of Fig. 1 turned through 90° in a counter-clockwise direction around a vertical axis.

Fig. 6 is an elevational view of the inside of one of the two identical frame members.

Fig. 7 is a sectional view along the line 7—7 of Fig. 6.

Fig. 8 is a detailed inside view of the stationary explosion head.

Fig. 9 is a detailed view of the combination paper support, paper feed, and cylinder closing unit.

Fig. 10 is a sectional view of the fastening structure for the two frame members.

In the illustrated embodiment of my invention I provide an elongated handle 10 which may be provided in two parts, telescoping together at a sleeve 11 rigidly secured on one portion of the handle for the ready reception of the other portion. With this structure the device may be conveniently packaged in a relatively short container, yet quickly fitted together by any user, including a small child. The lower portion 12 of the handle has rigidly secured thereto, a frame or a housing, including a pair of stamped-out identical frame members 13. Each frame member is provided with a laterally extending burr 14 on each of the securing apertures 16 along one side of such frame member. When the frame members are placed together in corresponding abutting relation, the burrs along one side of one frame member are inserted in corresponding apertures 16 on what would be the opposite side of the other or corresponding frame member. When upset in the final assembly of the frame, the burrs 14 along one side extend in one direction and are upset on the opposite side of the corresponding frame member (Fig. 10), and the burrs on the other side of the frame extend away from their integral frame member 13 in an opposite direction. This is shown particularly in Fig. 1 where the burrs 14 appear on the right-hand side of the figure, while the burrs 14 on the left-hand side of the figure extend in the opposite direction and are upset on what would be in that figure, the back of the frame. This structure eliminates the necessity of separable rivets or other fastening means thus simplifying the structure itself as well as the manufacture of the device.

Inwardly turned flanges 17 on the frame members limit the downward movement of the handle, and the metal of the frame members themselves adjacent the apertures 18 in each member is peened to drive such metal directly into the

wooden handle and thereby rigidly secure such frame on the handle.

Each of the frame members 13 extend down through convex integral explosion portions 19 and then through a cylinder carrying portion 21 to a cavity 22 which becomes a guide opening for the piston rod when the two frame members are secured together as shown in Figs. 1, 4 and 5, particularly.

- 10 The operating mechanism for the paper burster cane is entirely carried by the housing including the two identical frame members 13. This operating mechanism includes a cylinder 23 slidably carried in the portion 21 of the frame. A 15 piston rod 24, with a downwardly extending striker portion, is slidably supported in the cylinder 23 and retained therein by means of a friction cap 26 which may be driven into the lower end of the cylinder. The friction cap as shown in 20 Figs. 2 and 3 particularly, comprises a one-piece stamped-out member having side walls 27 tapering to such dimensions as to limit the distance to which the cap may be driven into the cylinder. A neck portion 28 is provided on the cap for receiving the piston rod 24 and maintaining the same, together with the aperture 22 of the frame, in alignment in the cylinder and frame. The friction cap 26 prevents the piston from being removed from the cylinder and also acts as a stop 25 for a coiled spring 29 surrounding the piston rod 24 and extending between a washer 31 at the striking end of the piston rod and such cap. The washer 31 is retained against rotation on the end of the piston rod by flattening the sides thereof as shown in Fig. 2 and is retained thereon by means of a striking pad 32 which comprises a piece of very sturdy rubber tubing having an inner aperture 33 considerably smaller in size than the flattened end portion 34 of the piston rod. 30 By virtue of this difference in size, the piece of tubing 32 is frictionally retained on the end of the piston rod and will withstand substantially any type of abuse in the operation of the toy. The striker pad 32 is slightly longer than the end portion 34 so that such end portion will be maintained out of contact with the floor or the like 35 against which the cane is pressed.

The piston itself comprises a cup-shaped leather member 36 secured in the top end of the piston rod 24 by means of an outside washer 37 keyed to the end of the piston rod as shown in Fig. 2 and an inside washer 38 similarly keyed to the piston rod and retained thereon by upsetting or peening the end of such rod at 39. As will be noted from Fig. 2, the washer 38 is smaller than the inside diameter of the piston cup 36, and the washer 37 substantially the same diameter as the outside diameter of the leather piston. This assembly permits of the maximum flexibility 40 of the leather piston itself, yet positively retains the same in position in spite of the most rigorous use of the toy.

The upper end of the cylinder 23 as viewed in Fig. 2 is rolled to form a flange 41 while a one-piece paper holder plate 42 is provided with a corresponding aperture and downwardly extending flange which is folded around and pressed upon the flange 41 to rigidly secure the paper holder to the cylinder so that it moves therewith. 45 A rubber grommet 43 is snapped into place at the cylinder opening and adapted to engage a stationary explosion head 44 as will be presently explained. As to the paper holder and feeding plate 42, this member together with the fastening means described above, and the feeding mecha-

nism hereinafter described is similar to the structure disclosed in my copending application, Serial No. 123,661. The plate 42 includes a paper carrying portion with slots 46 for receiving paper feeding teeth with said slots provided in an angular extending portion 47 as shown particularly in Figs. 2, 3 and 9. The roll of paper 48 is pivotally carried on a movable handle 49, integral with a mounting axis 51 non-removably secured in the arms 52 and 53 integral with the body portion 5 of the plate 42 and slanting downwardly and outwardly away from such body portion. The handle portion 49 is slightly resilient and snaps into a notch 54 in the arm 53. The paper is fed from the roll 48 over the feed portion 47 by means of a pivoted jaw 56 having downwardly extending teeth 57 and laterally extending ears 58, the latter pivotally secured in corresponding apertures 59 in each frame member. An integral tail 61 is notched at 62 to receive and retain a spring 63 secured under tension at one end around the pin 64, and bearing at the other end against the tail portion 61 as shown in Fig. 2. An embossed rib 66 extends from the body portion of the jaw upwardly through the tail for strengthening the 15 jaw member as a whole and also acting substantially as a pocket for the end of the spring 63 as shown in Fig. 2.

As previously noted, an explosion head (Fig. 8) is mounted by means of integral ears 67 in corresponding slots 68 on the frame members. Although the explosion head is non-rotatably and non-removably secured in the frame, there is a slight play therein axially of the cane by virtue of the width of the slot 68 and thickness of the 30 metal of the explosion head, so that the latter gives slightly as the grommet 43 presses the paper 35 48 against the same on an explosion stroke. The head may be pushed up to lie flat against the flange 69 at the top of the slot 68.

The assembly is completed with a retriever spring 71 extending from a stamped-out ear 72 on the one-piece member 42 and an integral ear 73 on one of the frame members 13. As shown in Fig. 1 only one of the ears 73 is used in the 40 assembly of the operating mechanism. With the two frame members 13 identical, however, the extra ear 73 of necessity results, and although only one of the two members has mechanical function, together they balance up the frame 45 50 from an aesthetic standpoint.

As to the operation of the torpedo cane, the paper roll 48 is first placed on the handle and axis 49 with the end of the paper being fed across the mouth of the cylinder grommet 43 and down intermediate the spring pressed jaw 56 and the paper supporting portion 47 on the member 42. The rubber striking tip 32 is placed on the sidewalk, floor, or the like and the handle is pushed downwardly. The spring 29 on the piston rod 24 acts to normally hold the piston rod in its extended position and also limit its movement in the cylinder 23. As pressure is exerted, however, the frame rigid on the handle 10 moves downwardly with reference to the piston rod 24 whereby the piston 36 moves upwardly in the cylinder 23. In the meantime, the spring tension in the spring 71 and possibly some slight friction between the outer surface of the cylinder 23 and the wall of the frame portion 21 holds the cylinder 70 stationary with respect to the frame, and consequently in the position shown in Figs. 2 and 3. When the piston is moved approximately to the position shown in Fig. 3 with reference to the cylinder, there is sufficient spring pressure built 75.

up in the coil spring 29, and bearing against the neck 28 of the cap 26 to force the cylinder upwardly. That is, the spring pressure causes movement between the cylinder and frame so that the cylinder occupies the position shown in Fig. 4, with the grommet 43 bearing against the paper 48 and the latter sealed against the embossed aperture portion 75 of the explosion head 44. The aperture 75 in the explosion head, of course, registers with the aperture in the grommet 43. On the balance of the downward movement of the handle, the piston is moved rapidly to its uppermost position shown in Fig. 4 to thereby compress the air intermediate the cylinder and paper sealed across the grommet to cause a bursting of such paper. As can be understood from an examination of Figs. 2 and 4, for instance, the paper is fed across the portion 47 of the paper supporting plate by means of a pivoted jaw 56 on the downward movement of the handle, and consequently the compression stroke of the piston and cylinder. After the paper has been bursted, the downward pressure is removed from the handle and the coil spring 28 forces the piston rod outwardly while the retrieving spring 71 pulls the cylinder to a position where the plate 42 engages shoulders 76 on each of the two frame members 13.

Although the assembly of the device is readily understood from the above description, it might be explained that the piston and piston rod assembly is completed and then inserted in the cylinder 23. The cap 26 may then be pushed over the rod 27 from the bottom thereof and pressed into the end of the cylinder in a tight frictional fit as shown in Fig. 3. The spring 29 is assembled on the piston rod and retained thereon by the washer 31 and rubber striking tip 32. All of the elements are assembled on one of the frame members 13 in a jig and then the corresponding frame member may be fastened thereto to retain all of the operating mechanism in or on the two-piece frame in a very sturdy fashion. The toy paper burster cane is, of course, harmless to operate and may be easily operated by any child. Because of its simplicity and ruggedness it will give long and satisfactory service under all types of treatment.

Although I have illustrated and described my invention in its preferred embodiment, it is understood that the invention is not limited thereby, but is limited only by the scope of the appended claims.

I claim:

- 55 1. A paper burster device including in combination a handle, a frame rigidly secured thereon, a cylinder in said frame aligned with said handle, a piston and piston rod unit in said cylinder, and means for retaining said piston in said cylinder comprising a cup-shaped apertured cap fitting over said piston rod having an annular wall adapted to be inserted in an end of said cylinder and tapered in such a manner that the diameter of the wall cross-section at the inner end thereof is less than the inside diameter of the cylinder and the corresponding diameter at the outer end of the wall is greater than the natural inside diameter of the cylinder whereby the cup is frictionally held in the end of the cylinder.
- 60 2. A paper burster device including in combination a rigid housing, a cylinder slidably carried within said housing, an apertured friction cap closing one end of the cylinder and an apertured plate rigidly secured to the cylinder at the other end thereof, a piston in said cylinder and

a piston rod therefor extending through said cap and out of said housing, a spring carried on said piston rod outside said cylinder acting to move the cylinder relative to said housing upon movement of said piston rod relative to said housing, but with the complete relative movement between said piston rod and housing varying from the complete relative movement between said cylinder and housing, said spring returning the piston rod to its original position with respect to the cylinder, means for positioning paper across the apertured plate end of the cylinder to be burst upon compressing the air in the cylinder.

3. A paper burster device including in combination, a rigid housing, a cylinder slidably supported within said housing, a piston and piston rod assembly slidable within said cylinder, apertured closing means for said cylinder at one end comprising an apertured plate rigidly secured to the end of the cylinder and extending laterally out of said housing in opposite directions, paper holder means on said plate at one end outside said housing and a paper carrying portion on said plate at the other end thereof outside said housing with said plate movable with said cylinder, a paper feeding jaw pivoted on said housing acting to feed paper from said holder means over said paper carrying portion upon movement of said cylinder to paper bursting position, means for causing movement of said cylinder relative to said housing upon movement of said piston rod relative to said housing, and a recoil spring to return said cylinder from paper bursting position to normal non-operating position.

4. In a paper burster toy, a frame, a compression cylinder slidably carried within the frame having a lateral extension on one end thereof extending out of the frame, a piston and piston rod unit in said cylinder, means for causing movement between said cylinder and frame upon relative movement between said piston rod and frame to place said cylinder in paper bursting position, and spring means on the outside of said frame secured at one end to said frame, and at the other end to said lateral extension to return said cylinder to non-operating position after the bursting of the paper.

5. In a paper burster toy, a compression cylinder slidable in said frame having an explosion aperture at one end, and apertured closing means at the other end, a piston rod extending out of said cylinder through the aperture of said closing means and extending out of the frame for an actuating engagement, and a spring on said piston rod extending from the apertured closing means for said cylinder to a step at the engaging end of said piston rod acting to move the cylinder in said frame upon relative movement of the frame.

6. A paper burster device including in combination a cylinder, a piston and piston rod unit in said cylinder, and means for retaining said piston in said cylinder comprising a cup-shaped apertured cap fitting over said piston rod having an annular wall adapted to be inserted in an end of said cylinder and tapered in such a manner that the diameter of the wall cross-section at the inner end thereof is less than the inside diameter of the cylinder and the corresponding diameter at the outer end of the wall is greater than the natural inside diameter of the cylinder whereby the cup is frictionally held in the end of the cylinder.

7. A paper burster device including in combination a handle adapted to be grasped by one
